Patented Dec. 4, 1917.

Fig. 1.

UNITED STATES PATENT OFFICE.

EDWARD HINES, OF PHILADELPHIA, PENNSYLVANIA, ASSIGNOR OF ONE-HALF TO
WILLIAM H. BROOKS, OF ST. DAVIDS, PENNSYLVANIA.

DEINKING-MACHINE FOR PLATEN-WIPERS.

1,249,085.

Specification of Letters Patent. Patented Dec. 4, 1917.

Application filed July 26, 1917. Serial No. 182,838.

To all whom it may concern:

Be it known that I, EDWARD HINES, a citizen of the United States, residing in the city and county of Philadelphia, State of Pennsylvania, have invented a new and useful Deinking-Machine for Platen-Wipers, of which the following is a specification.

In power operated stamping presses of the plate and die type as ordinarily used a wiper is employed in the form of a platen which is ordinarily paper, and on this paper the ink is collected. Unless means are employed to remove the ink from the paper there is a considerable loss in the consumption of the amount of ink employed, and also a considerable loss of paper.

It is the object of my present invention to devise novel means for recovering the ink from the paper in such a manner that both the ink and paper can be used over again.

With the above in view my invention comprehends a novel construction of a deinking machine for platen wipers.

Other novel features of construction and advantage will hereinafter appear in the detailed description of my invention.

For the purpose of illustrating my invention I have shown in the accompanying drawing a typical embodiment of it which in practice will give satisfactory and reliable results. It is, however, to be understood that the various instrumentalities of which my invention consists can be variously arranged and organized, and that my invention is not limited to the exact arrangement and organization of these instrumentalities as herein set forth.

Figure 1 represents a top plan view of a deinking machine for platen wipers embodying my invention.

Fig. 2 represents a section on line 2—2 of Fig. 1.

Similar numerals of reference indicate corresponding parts in the figures. Referring to the drawings.

The deinking machine is secured with respect to the stamping press in any desired manner, and I have therefore deemed it unnecessary to illustrate the stamping press. 1 designates the base of a deinking machine for platen wipers embodying my invention, said base being provided with the side members 2. 3 designates the platen which first passes over a roll 4, the ends of 55 which are freely rotatable in the slot 5 of

the bracket 6 secured in any desired manner to the side members 2. The slot 5 opens laterally through the bracket 6 and pins 7 are provided which pass through the bracket 6, and maintain the roll 4 in assembled position. The platen 3 then passes beneath a roll 8 journaled in arms 9 integral with or connected to the side members 2. After leaving the roll 8 the platen 3 passes upwardly over a scraping blade 10 which is mounted in inclined slots 11 in the side members 2.

In order to adjust the height of the scrapers 10, set screws 12 are provided in threaded engagement with the side members 2, and having their upper ends bearing against the lower ends of said scrapers. The platen 3 then passes over a composition roll 13 mounted on a shaft 14 which is journaled in slots 15 in the side members 2. 70 This roll extends into a pan 16 which is substantially trough shape, and provided at its ends with flanges 17 which rest on the side members 2. The roll 13 is in contact with the solvent 18 such as for example 75 turpentine and coal oil, it being understood that any desired or suitable material may be employed for this purpose.

The pan 16 forms a solvent container and is provided with a discharge spout 19. The platen passes over the roll 13, and then downwardly beneath a roll 20, the ends of which are journaled in the side members 2 in any desired manner. The platen then passes upwardly over a scraper 21 the ends of which are mounted in the inclined slots 22 in the side members 2. Set screws 23 are provided in threaded engagement with the side members 2 and adapted to contact with the scraper 21 in order to effect its 90 vertical adjustment.

Set screws 24 are also provided which are in threaded engagement with the side members 2 and bear against the scraper 21 in order to lock it in its adjusted position. 100

The platen 3 then passes over a cleaning roll 25 the surface of which is covered with absorbent material 26 and the ends of this roll are journaled in slots 27 in the side members 2. The platen 3 then passes beneath a roll 28 journaled in the side members 2 and therefrom to a desired point of utilization.

The base 1 is provided with a pan 29 with in which is placed the pans 30 and 31, the 110

pan 30 serving to collect the ink removed by the scraper 10, and the pan 31 serving to collect the oil and ink removed by the scraper 21, and the cleaning roll 25.

5 In order to maintain the supply of solvent in the solvent container 16, I provide a pipe 32 leading from a source of solvent supply (not shown), and discharging into the solvent container 16.

10 The operation will now be readily understood by those skilled in this art and is as follows:—

The platen 3 which serves as a wiper has one side thereof coated with ink as it comes 15 out of the stamping press. In passing over the scraper 10 the greater part of this ink carried by the platen is removed and falls into the collecting pan 30. The platen then passes over the roller 13 which causes the 20 ink solvent to come into contact with the paper, so that when the platen passes over the second scraper 21 the solvent and ink will be scraped therefrom and dropped into the collecting pan 31. The platen then 25 passes over the roller 25 which acts as a cleaning roller to remove the oil and ink from the platen.

The platen is now in such condition so that it can be used over again as a wiper, 30 and the ink in the pans 30 and 31 is in such condition that it can also be used again.

In many cases arising in practice the rollers 4 and 8 can be dispensed with if desired.

35 The rolls 13, 20, 25 and 28 are preferably journaled in the same horizontal plane, and the rolls 20 and 28 have preferably a smaller diameter than the rolls 13 and 25, while the roll 25 is preferably of less diameter than 40 the roll 13.

It will be apparent that the base and side members form a support or framework in which the various rolls are journaled.

Having thus described my invention what 45 I claim as new and desire to secure by Letters Patent, is:—

1. In a deinking machine, a support, a solvent roll rotatably carried by said support, a scraper carried by said support anterior to said solvent roll, a second scraper carried by said support posterior to said solvent roll, a cleaning roll carried by said support posterior to said second scraper, and a platen in the path of which said solvent rolls, said scrapers and said cleaning roll are located.

2. In a deinking machine, a support, a solvent roll rotatably carried by said support, a scraper carried by said support anterior to said solvent roll, a second scraper carried by said support posterior to said solvent roll, a cleaning roll carried by said support posterior to said second scraper and provided with a solvent surface, and a 65 platen in the path of which said solvent

rolls, said scrapers and said cleaning roll are located.

3. In a deinking machine, a support comprising a base and upwardly extending sides, scrapers adjustably mounted in said sides, a solvent roller journaled in said sides between said scrapers, a cleaning roll journaled in said sides posterior to said scrapers, and a platen in the path of which said scrapers, solvent roll and cleaning roll 75 are located.

4. A deinking machine comprising a support having a base and side members, pans carried by said base, scrapers carried by said side members, a solvent roll journaled in said side members above one of said pans, and positioned between said scrapers, and a cleaning roll having an absorbent surface and journaled in said side members above the other of said pans, in combination with 80 a platen in the path of which said scrapers, solvent roll and cleaning roll are mounted.

5. In a deinking machine, a support comprising a base and side members, a solvent roll journaled in said side members, a 90 solvent container carried by said side members and into which said solvent roll extends, a scraper carried by said side members anterior to said solvent roll, a scraper carried by said side members posterior to 95 said solvent roll, and a cleaning roll journaled in said side members posterior to said solvent roll and scrapers.

6. In a deinking machine, a support, a solvent roll journaled in said support, a 100 solvent container in proximity to said solvent roll, a scraper carried by said support anterior to said solvent roll, a scraper carried by said support posterior to said solvent roll, a cleaning roll carried by said support posterior to said scrapers, a platen and rolls carried by said support to maintain said platen in operative relation with respect to said scrapers, said solvent roll, and said cleaning roll.

7. In a deinking machine, a support comprising a base and side members, a solvent roll journaled in said side members, a scraper carried by said side members anterior to said solvent roll, a scraper carried by said side members posterior to said solvent roll, a solvent container into which said solvent roll extends, a platen in the path of which said scrapers and solvent roll are mounted, and a pan carried by said support, said solvent container having an overflow discharging into said pan.

8. In a deinking machine, a support comprising a base and side members, pans carried by said support, a solvent roll journaled in said side members, a scraper carried by said side members anterior to said solvent roll and located above one of said pans, a second scraper carried by said side members posterior to said solvent roll and 130

located above the other of said pans, a cleaning roll having an absorbent material on its periphery and journaled in said side members posterior to said scrapers, a platen, 5 means to maintain it in engagement with said scrapers, said solvent roll and cleaning roll, and a solvent container carried by said

side members and having an overflow discharging into one of said pans.

EDWARD HINES.
